[57] CLAIM

The ornamental design for a board game, as shown and described.

DESCRIPTION

FIG. 1 is a perspective view of a board game showing my new design;

FIG. 2 is a front elevational view thereof;

FIG. 3 is a top plan view thereof;

FIG. 4 is a side elevational view thereof;

FIG. 5 is a rear elevational view thereof; and,

FIG. 6 is a bottom plan view thereof.

The broken lines are for illustrative purposes only, and forms no part of the claimed design.
